SPECIFICATION forming part of Design No. 18,726, dated November 13, 1888.

Application filed October 6, 1888. Serial No. 287,585. Term of patent 7 years.

To all whom it may concern:

Be it known that I, FREDERICK BEIERMEISTER, Jr., a citizen of the United States, residing at the city of Troy, in the county of 5 Rensselaer and State of New York, have invented and produced a new and original Design for Apparel-Collars, of which the following is a specification, reference being had to the accompanying drawings, forming a part 10 thereof.

Figure 1 is a view in perspective of my newly-designed collar. Fig. 2 is a top plan view of the same in outline.

The leading feature of my design consists of 15 a straight end edge extending in a vertical line from the upper part of the collar to the button-hole tab, and a triangular-shaped retroverted tab having one of its triangular edges coincident with the end edge of the collar and 20 extending from the button-hole tab part way only to the top of the collar, one on each collar end.

A A' are the retroverted triangular-shaped 25 tabs, connected with the ends of the collar C, one with each end, by vertical folds along the triangular edges D D' of the tabs. The edges B B' and D D' form one and the same straight vertical line and constitute the vertical end edges of the collar, extending from the upper edge of the collar to the button-hole tabs E E', 30 the edges D D' forming one of the triangular sides of the tabs, extending from the button-hole tabs part way only to the top of the collar.

What I claim as new is—

The design for an apparel-collar herein shown and described, the same consisting of straight end edges extending in a vertical line from the upper part of the collar to button-hole tabs on the lower part, and a triangular-shaped retroverted tab, one on each collar end, having one 35 of its triangular edges coincident with the end edge of the collar and extending from the button-hole tab part way only to the top of the collar. 40

In testimony whereof I have hereunto set my hand this 5th day of October, 1888.
